VACUUM CLEANER

James F. Mariol, Cincinnati, Ohio, assignor to Vernco Corporation, Columbus, Ind., a corporation of Indiana

Filed Apr. 16, 1968, Ser. No. 11,481

Term of patent 14 years

Int. Cl. D7—06

U.S. Cl. D49—14.1

Fig. 1

Fig. 2

Fig. 3

Fig. 4

FIG. 1 is a perspective view, drawn to a reduced scale, of a vacuum cleaner embodying my design;

FIG. 2 is a top plan view thereof;

FIG. 3 is a side elevational view thereof; and

FIG. 4 is another side elevational view thereof seen generally from the left-hand side of FIG. 3.

I claim:

The ornamental design for a vacuum cleaner, as shown and described.
